UNITED STATES PATENT OFFICE.

ISADORE S. DIEHL, OF ALLENTEW, PENNSYLVANIA.

GEARING FOR WASHING-MACHINES.

SPECIFICATION forming part of Letters Patent No. 717,974, dated January 6, 1903.

Application filed March 5, 1902. Serial No. 96,807. (No model.)

To all whom it may concern:

Be it known that I, ISADORE S. DIEHL, of Allentown, in the county of Lehigh and State of Pennsylvania, have invented certain new and useful Improvements in Gearing for Washing-Machines; and I do hereby declare the following to be a full, clear, and exact description of the invention, such as will enable others skilled in the art to which it appertains to make and use the same.

The object of this invention is to provide improved, simple, and highly-efficient mechanism for imparting an alternating rotary motion to the rubber of a washing-machine.

The invention will be hereinafter fully set forth, and particularly pointed out in the claims.

In the accompanying drawings, Figure 1 is a view in perspective, showing portion of a tub with the operating mechanism mounted on the top thereof. Fig. 2 is a top plan view. Fig. 3 is a view in perspective, showing part of the rack-bar and its supporting-bracket. Fig. 4 is a sectional view on line $x-x$, Fig. 1.

Referring to the drawings, 1 designates a tub or casing designed to contain a rotary rubber 2 and having a lid 3 on which the operating mechanism is mounted. The casing and rubber are well known and may be of any preferred construction.

4 designates an upright frame suitably mounted on the top or lid of the casing.

5 is a driving gear-wheel having its journal supported in bearings in the frame and designed to mesh with pinions 6 and 7. Pinion 6 is fast on a shaft 8, which extends through the frame and on which is keyed a balance-wheel 9. Pinion 7 is fast on a shaft 10, which also extends through the frame beyond the plane of wheel 9, and on its outer end is a handle 12.

13 designates a rack-bar pivotally connected to gear-wheel 5 and supported in a bracket 14 on frame 4. A pinion 15 of less cross-sectional diameter than the driving gear-wheel meshes with the rack-bar and is fast on a shaft 16, supported between bearings on the frame and an upright 17, mounted on the lid of the casing. Also fast on shaft 16 is a large bevel gear-wheel 18, meshing with a pinion 19, fast on a hub 20, which passes through the lid of the casing and is fast on the stem

21 of the rubber, said stem being supported at its upper end by an overhanging portion 22 of upright 17. A collar 23, secured to the lid, forms the bearing for a flange on hub 20.

In practice the operator turns handle 12 steadily in either direction, the pinion 7 actuating gear-wheel 5 and effecting the rotation of wheel 9 through pinion 6, thus imparting a well-balanced rotary motion to the gear-wheel 5. Rack-bar 13 is positively actuated to effect an alternating rotary motion to pinion 15 and through the gear-wheel 18 and pinion 19 to insure a corresponding motion of the rubber 2.

The advantages of my invention are apparent to those skilled in the art.

I claim as my invention—

1. A gearing comprising a driving gear-wheel, means for operating the same, a rack-bar pivotally secured to said driving gear-wheel, a pinion meshing with said rack-bar, a gear-wheel moving in unison with said pinion and a second pinion meshing with said gear-wheel, substantially as set forth.

2. A gearing comprising a driving gear-wheel, means for operating the same, a rack-bar pivotally secured direct to said driving gear-wheel, a pinion meshing with said rack-bar, said pinion being of less cross-sectional diameter than said driving gear-wheel, for the purpose set forth, a gear-wheel moving in unison with said pinion, and a second pinion meshing with said gear-wheel.

3. A gearing comprising an upright frame, a driving gear-wheel supported thereby, means for operating the same, a rack-bar pivotally secured to said driving gear-wheel, a pinion meshing with said rack-bar, a bracket secured to said frame and holding said rack-bar in mesh with said pinion, an upright, a shaft supported by said frame and said upright, said pinion being fast on said shaft, a gear-wheel also fast on said shaft, and a pinion meshing with said gear-wheel, substantially as set forth.

4. A gearing comprising an upright frame, a driving gear-wheel supported thereby, means for operating the same, a shaft extending through said frame, a pinion fast on one end of said shaft meshing with said gear-wheel, a balance-wheel fast on the other end of said shaft, a rack-bar pivotally secured to said

driving gear-wheel, a pinion meshing with said rack-bar, a bracket secured to said frame and holding said rack-bar in mesh with said pinion, an upright, a shaft supported by said frame and said upright, said pinion being fast on said shaft, a gear-wheel also fast on said shaft, and a pinion meshing with said gear-wheel, substantially as set forth.

5. In gearing the combination of an upright 10 having an overhanging portion provided with a bearing, a vertical shaft mounted in said bearing, and having a hub suitably mounted in alinement with said bearing, a pinion fast on said hub, a driving gear-wheel and means

for operating the same, a rack-bar pivotally secured to said driving gear-wheel, a pinion meshing with said rack-bar, and a gear-wheel moving in unison with said pinion and meshing with the pinion on said hub, substantially as set forth.

20 In testimony whereof I have signed this specification in the presence of two subscribing witnesses.

ISADORE S. DIEHL.
